UNITED STATES PATENT OFFICE.

GEORGE P. BRAND, OF NEW YORK, N. Y.

PEDAL-OPERATED EXHAUST MECHANISM FOR AUTOMATIC MUSICAL INSTRUMENTS.

1,420,238.

Specification of Letters Patent. Patented June 20, 1922.

Application filed October 29, 1917. Serial No. 199,140.

To all whom it may concern:

Be it known that I, GEORGE P. BRAND, a citizen of the United States, residing at the city of New York, borough of Bronx, in 5 the county of Bronx and State of New York, have invented certain new and useful Improvements in Pedal-Operated Exhaust Mechanism for Automatic Musical Instruments, of which the following is a specification.

This invention relates to certain new and useful improvements in player piano expression mechanism, and pertains more especially to the bottom action or exhaust mechanism actuated by the pedals or analogous means.

The present invention has for its objects among others to provide very sensitive pedaling effects without causing any disagreeable resistance or chattering of the pedals caused by the displacement of the air being drawn from the action while in operation.

Heretofore many different forms of devices have been employed for producing accenting results by movement of the pedals, such as crash valves and the like, but the use of crash valves necessitates quick or sudden depression of the pedals to cause said valves to close and cut out the bellows in 25 which they are placed, thus rendering the accenting results uncertain and unreliable. In devices where crash valves are employed the springs employed are necessarily of such strength that to play on soft pressure the bellows must be distended to their fullest extent, thereby not having pressure beyond working pressure. Consequently, as soon as the movement of the pedals ceases for an instant or so, there is no pressure to continue the working of the player or rendition 30 of the composition.

Another object of the invention is to attain greater carrying capacity of the low pressure. To get real artistic results and 45 smooth rendition of compositions, it is necessary to have entire control of the low pressure and it is necessary to have the low pressure of the machine so reliable as to not "fall away," as it is called, from the feet and 50 cause the performer uneasiness by reason of not being sure but what the player may stop at any point between the up and down strokes of the pedals. Most players have so much spring tension in the reservoirs that 55 one has to keep much too high a pressure

in the player to be sure that the machine is perfectly reliable to render the playing of all of the notes. If the reservoirs are made to work nicely on low pressure, then there is a disagreeable resistance when working 60 under high pressure.

These disadvantages are overcome by my present improvement in which I employ what I term a cushion bellows and a concussion bellows to assist in making the pedals very sensitive and easily operated and possessing greater power with less energy on the part of the performer and at the same time insuring very fine musical results and reliability in action. My present improvement also is an aid to the novice in learning 65 to play as the pedaling is easy and more natural and sudden depression of the pedals is obviated.

By "cushion bellows" I mean the main 75 reservoir, or reservoirs, cushioned so that with a sudden push on the pedal for the purpose of producing accentuations the bellows collapses without producing the noise that otherwise would occur by the sudden 80 collapse of the reservoir, the cushion being located adjacent the heel or hinge end of the bellows, so that the said cushion serves to check the momentum upon the initial movement of the bellows, and then forms 85 a yielding resistance to the further collapse of the bellows.

By "concussion bellows" I mean a bellows that cooperates with the cushion bellows and is brought into action after the cushion bellows has collapsed sufficiently to bring about the cushioning effect, as above described, and having a valve controlled deflation port of sufficient size to allow of quick deflation and a continuously open restricted inflation 90 port to retard or compel slow inflation. This will be clearly understood by the description of the operation later on.

I may sometimes employ what I term a compensating spring to compensate for the 100 different positions of the reservoir in causing the pressure to be practically the same at any position of the reservoir, giving an even carrying capacity on low pressure.

Furthermore, by my present improvement 105 it is desirable at all times to feel the pressure under which the performer is playing, no matter whether it be the reaction of a high pressure or low pressure against the foot on the pedal, so that the performer feels 110

confident in rendering the notes as he desires. This also is assured by my present improvement.

Other objects and advantages of the invention will hereinafter appear and the novel features thereof will be particularly pointed out in the appended claims.

The invention is clearly illustrated in the accompanying drawings, which, with the numerals of reference marked thereon, form a part of this specification, and in which—

Figure 1 is a vertical transverse section on the line 1—1 of Figure 2.

Figure 2 is a face view with parts broken away.

Figure 3 is a detail of a modified form of pedal-operated bellows or exhaust mechanism.

Figure 4 is an end view of Figure 3.

Figure 5 shows still another form of pedal-operated or exhaust mechanism.

Figure 6 is an end view thereof with the channel member in section.

Figure 7 is a section on the line 7—7 of Figure 2.

Figure 8 is a sectional detail showing the reservoir and associated parts in playing position.

Like numerals of reference indicate like parts throughout the several views.

Referring to the drawings,

1 designates a casing or enclosure within which the pedals are adapted to be folded when not in use. This case serves also as a support for the exhaust mechanism soon to be described. The folding pedals, however, do not form a part of the present invention, being covered by a separate application. 2 are the pedals pivotally connected, as at 3, with the arms 4 which, in turn, are pivoted, as at 5, to the curved arms 6 pivoted, as at 7, intermediate their length within the casing and at their upper ends pivotally connected, as at 8, with the arms 9 which are attached to the lugs 10 attached to the exhauster 11, whereby pressure upon the pedals will cause the movable leaf of the exhauster to move outward. Further than this it is not deemed necessary to describe the construction or mode of operation of the pedals.

The exhaust mechanism is mounted upon the case 1 in any suitable manner, as for instance by the plates 12 secured to the sides of the casing, as at 13, and to the under side of the reservoir, as at 14, see Figure 1. The exhaust mechanism comprises the exhauster 11 before mentioned provided with a removable plate 15 having a plurality of ports 16 covered by a pallet 17 well-known in the art and a detailed description of which is not deemed necessary, the pallet being secured to the plate 15 in any well-known way, the reservoir or tension bellows 18 the stationary member 19 of which has a plurality of open-

ings 20 therethrough covered by the pallet 21 secured in any well-known manner, as common in the art, and the concussion bellows 22. The exhausters 11 are secured to the reservoir 18 and the concussion bellows 22 are secured one to the outer end of each of the exhausters 11, as shown best in Figure 2.

The reservoir is connected through the port 23 in the stationary wall thereof and through the port 24 to the nipple or the like 25 adapted for connection by a flexible tube or analogous means 26 with any well-known action chest which operates the notes of the ployer, 27 being a striker pneumatic and 28 the tube for connection with the trackerbar, not shown.

Each concussion bellows 22 is connected by a small tube 29 with the adjacent end of the reservoir 18, as seen clearly in Figure 2. Each concussion bellows has a spring 30 of the usual V type, tending to distend the bellows against pressure. The reservoir 18 is provided at each end with a smaller V spring 31 for a similar purpose, but of much less strength than the springs 30, for a purpose soon to be described.

The stationary member of the concussion bellows 22 is provided with an opening 32 for connection of the tube 29, as seen clearly in Figure 7. This stationary member is provided with a port 33 covered by a flap valve 34 which may be held to its seat by a light tension spring 35, as seen in Figure 7.

In the interior of the reservoir I provide a cushion 36 of some soft material, such as felt or the like, which serves as a yieldable stop or cushion for the movable member of the reservoir 18 when accenting takes place or playing under heavy pressure.

In Figure 3 I have shown a slightly modified form of arrangement of the exhauster mechanism. In this figure 11^a are the exhausters, 18^a the reservoir and 22^a the concussion bellows. 29^a are the connections between the concussion bellows and the reservoir.

37 is a compensating spring for increasing the resistance on the reservoir as it is inflated and decreasing the pressure as the reservoir is deflated and compensates for the atmospheric pressure on the cloth during the movement thereof. One end of this spring is attached at 38 to an arm or the like 39 secured to the stationary member of the reservoir and its other end attached, preferably adjustably, as at 40, to the movable member of the reservoir, as seen in Figure 4.

In Figures 5 and 6 I have shown still another form of arrangement of the parts constituting the exhaust mechanism. In this form the exhausters 11^b are shown as carrying the concussion bellows 22^b, but in this instance there is a reservoir 18^b at each end. 41 is a duct or channel affording communica-

cation between the two reservoirs 18^b, the said channel being also in communication with the exhausters in substantially the same way as the connections between the reservoir and exhauster in Figure 1.

With the parts constructed and arranged substantially as hereinbefore described, the operation, briefly set forth, is as follows:—

The performer upon placing his feet upon 10 the pedals and pressing downward thereupon, starts the machine playing. If it is desired to play very soft, the performer pumps a little slower on his pedals to produce the desired amount of energy desired 15 to play the composition he is rendering, thereby allowing the reservoir to get its resistance from the springs 31 set at the proper tension to produce the required pressure to produce the best results. Now if the performer 20 desires to accent any particular note or notes, he exerts more pressure upon the pedals and gets a greater resistance, causing the reservoir to collapse against the cushion 36. At the same time his concussion 25 bellows will collapse in accordance with the amount of pressure he puts on the pedals. Now if he desires to produce a "crash" or a very heavy accent, he exerts greater pressure upon the pedals and causes the reservoir 30 to depress the cushion a little more and the concussion bellows at the same time will be drawn in to its closed position. It is desirable after a "crash" or a heavy accent for the pressure to return to medium soft 35 pressure without remaining at high pressure too long. This is accomplished by employing a cushion which will depress just a short distance, not requiring too much inflation to relieve that pressure and also by 40 restricting the passage between the concussion bellows and the reservoir, so that upon release of the pressure on the pedals the concussion bellows glides back slowly by the air being drawn through the reservoir through 45 the restricted or small tube 29. This takes place continuously by the depression of either pedal with either foot and the concussion bellows is continually feeding or drawing air from the reservoir from the 50 different accents of the feet on the pedals which causes the concussion bellows to be drawn in more or less, according to the pressure on the pedals, giving the exhaust mechanism a greater carrying capacity and allowing of greater contrast of expression 55 through the use of the pedals.

The springs 30 of the concussion bellows are made very much heavier than are the springs 31 of the reservoir, so that they offer 60 greater resistance to the pedals so as not to operate only when accenting is desired and then operating in accordance with the force of the accent produced. Under very light pressure the springs 30 are not affected. 65 The concussion bellows are employed for the

purpose of giving elastic feeling to the pedals and allowing the reservoir to be cushioned and adjusted to the most sensitive touch, at the same time supplying light pressure energy to the reservoir after the 70 concussion bellows have been drawn toward their deflated position. The concussion bellows serve to store up energy without affecting the musical results of the reservoir during playing under ordinary conditions. 75

As is well known, the reservoir is the common receptacle for the air from all parts of the player as this reservoir is always under more or less exhaust tension through its springs and cushion. This tension is created by the movement of the pedals and, consequently, the exhausters. This being the case, after the note or notes are accented, the displacement of the air from the different parts of the player being drawn into 80 the reservoir relieves the reservoir of the tension just produced by the depression of the pedals.

It being understood that when enough pressure is exerted upon the pedals to bring 90 the movable leaf down against the cushion, tension will be produced in the reservoir in accordance with whatever pressure is being exerted on the pedals. After this condition has arisen in the reservoir, it is desirable to 95 relieve this tension as quickly as possible and I depend on the displacement of the air from the parts of the player to relieve this condition in the reservoir. Therefore, I restrict the connection between the concussion 100 bellows and the reservoir to such a degree as to not have the concussion bellows interfere with this desired result and still, at the same time, assist the reservoir in supplying the carrying capacity of the lower tensions or pressures. So, it is plainly seen that I accomplish two results by the use of the concussion bellows; one, to give the elastic 105 feeling upon the pedals when accenting or keeping the movable leaf of the reservoir against the cushion by the pedals, and, second, on the release of the pedals the concussion bellows are continually assisting the reservoir in its low pressure capacity and allows the performer to press his feet down 110 and practically caress the pedals with his feet to produce the desired results, the same as when playing upon the keys of the piano by hand.

The operation is substantially the same 120 whether I employ one or more reservoirs, or whether the arrangement be that shown in Figure 2, or that of Figure 3, or that of Figure 5. It is to be understood that the interior construction and co-relation of parts 125 is substantially the same in all of the different forms herein illustrated.

While I have shown in the present instance the concussion bellows as connected by its restricted tube with the reservoir, this 130

is not necessary as this restricted communication may be between the concussion bellows and the action chest of the player or any other part thereof which has to do with the playing tension of the player, the result being the same.

Modifications in details may be resorted to without departing from the spirit of the invention or sacrificing any of its advantages.

10. What is claimed as new is:—

1. In an automatic music player, the combination of an air tension member, an ex-
hauster, a concussion bellows in valved de-
flating communication therewith, and a re-
stricted inflating communication between
15 said concussion bellows and said air tension
member.

2. In an automatic music player, the com-
bination of an air tension member, an ex-
hauster, a concussion bellows in valved de-
flating communication therewith, and a re-
stricted inflating communication between
20 said concussion bellows and said air tension
member, the passage through said restricted
communication being always open.

3. The combination of a plurality of ex-
hausters, a tension member with which they
communicate, and a concussion bellows for
each exhauster, in valved deflating com-
30 munication therewith and at all times in re-
stricted communication with said tension
member.

4. The combination of a plurality of ex-
hausters, a tension member with which they
communicate, and a concussion bellows for
each exhauster, in valved deflating commu-
35 nication therewith and at all times in com-
munication with said tension member, there
being a restricted inlet to each concussion
bellows.

5. The combination of an exhauster, and
a concussion bellows having a deflation port
and an independent restricted inlet to re-
tard inflation only.

45. 6. The combination of an exhauster, a
plurality of concussion bellows, and valves
controlling the deflation of said bellows.

7. The combination of a plurality of ex-
hausters, and a plurality of concussion bel-
50 lows in communication therewith, and means
for rendering such communication alter-
nately direct and indirect.

8. The combination of an exhauster, a
concussion bellows in communication there-

with, and an intermediate valved deflation
port controlling such communication, and a 55
restricted inflation port.

9. The combination of a plurality of ex-
hausters, a concussion bellows for each ex-
hauster, each of said exhausters being in di-
rect communication with one of said con-
cussion bellows and indirectly with the
other.

10. The combination of a cushion bellows
and a concussion bellows arranged to give
65 elastic results to the pedals and means for
causing the same to assist in the low-car-
rying capacity of the wind-inducing devices.

11. The combination of a low tension res-
ervoir, and a high tension concussion bel-
lows, and means for causing said concussion 70
bellows to assist the low-carrying capacity
of the same.

12. The combination of a low tension res-
ervoir, a high tension concussion bellows,
and means for causing said concussion bel-
lows to assist the low-carrying capacity of
75 the same, and means for exhausting the air
from said reservoir and bellows.

13. The combination of a reservoir, an ex-
hauster, and a compensating resistance 80
means acting to maintain an even tension in
said reservoir, the force exerted by said
means increasing with the distension of the
reservoir and decreasing as the reservoir col-
apses.

85. 14. The combination of a reservoir, an ex-
hauster, and a compensating resistance means
means acting upon the movable member of
said reservoir to maintain an even tension in
said reservoir when the tension is being cre-
90 ated therein by said exhauster, the force ex-
erted by said means increasing as the reser-
voir is distended and decreasing as the
reservoir collapses.

95. 15. The combination of a reservoir, an ex-
hauster, a compensating resistance means
means acting upon the movable member of said
reservoir to maintain an even tension in said
reservoir while the tension is being created
100 therein by said exhauster, the force of said
means increasing as the reservoir is distend-
ed and decreasing as the reservoir collapses
and means for adjusting the tension of said
spring.

In testimony whereof I affix my signa-
ture.

GEORGE P. BRAND.
